(57) **CLAIM**

The ornamental design for a clustered electric-jet-powered vertical takeoff and landing aircraft as shown and described.

DESCRIPTION

FIG. 1 is a front perspective view of a clustered electric-jet-powered vertical takeoff and landing aircraft showing our new design;

FIG. 2 is a front perspective with open louvres;

FIG. 3 is a rear perspective view;

FIG. 4 is a bottom perspective view;

FIG. 5 is a top view;

FIG. 6 is a bottom view;

FIG. 7 is a front view;

FIG. 8 is a rear view;

FIG. 9 is a left side view; and,

FIG. 10 is a right side view.
